UNITED STATES PATENT OFFICE.

THOMAS FRANK LITAKER, OF FELLOWS, CALIFORNIA.

ROTARY DRILL.

1,114,375.

Specification of Letters Patent. Patented Oct. 20, 1914.

Application filed January 24, 1914. Serial No. 814,179.

To all whom it may concern:

Be it known that I, THOMAS F. LITAKER, a citizen of the United States, residing at Fellows, in the county of Kern and State 5 of California, have invented a new and useful Rotary Drill, of which the following is a specification.

This invention relates to rotary drills for use in working stone and the like, the same 10 being more particularly designed as an improvement upon the structure disclosed in patent No. 1,046,615, issued to me on December 10, 1912.

One of the objects of the invention is to 15 provide a stronger and more efficient structure than has heretofore been devised and to employ improved means for engaging and cutting into the work, said means being attached to the head of the tool in a new 20 and novel manner whereby accidental separation of the parts while in use is prevented.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 30 within the scope of what is claimed, without departing from the spirit of the invention.

In the accompanying drawings the preferred form of the invention has been shown.

In said drawings:—Figure 1 is a side elevation of the drill. Fig. 2 is a view partly in front elevation and partly in section. Fig. 3 is an end elevation.

Referring to the figures by characters of reference 1 designates the head of the drill 40 and formed at one end of this head is a threaded stem 2 adapted to engage a tubular drill rod, not shown. The head 1 is provided with spaced legs 3 oppositely disposed and forming an arch, and extending longitudinally through the stem 2 and the head 1 and opening into the arch is a bore 4 adapted to receive a tubular lining 5. This lining has an annular flange 6 at its upper end for limiting its downward movement in the bore 45 and the interior of the lining can be of any desired diameter. The legs 3 are oppositely disposed and have their outer faces rounded 50 as shown in Fig. 3 while the lower portions

of their inner faces are parallel and directly opposed. Secured to these parallel faces 7 55 are wear plates 8 and an opening 9 extends through each wear plate and the leg to which it is attached, this opening being adapted to receive the threaded portion 10 of a bearing pin 11. Said bearing pin is 60 provided, at its inner end, with a head 12 and between the head and the threaded portion is a cylindrical portion 13 on which a cutting disk 14 is adapted to rotate. The threaded portion 10 of the pin is screwed 65 into the leg 3 and unscrewing of the pin is prevented by means of a cotter pin 14' or the like extended through the pin 11 outside of the leg 3.

The disk 14 is concavo-convex, the convex 70 face thereof being stepped annularly as shown at 15 so as thus to be reinforced. The two disks are directly opposed to each other and are of like proportions.

It is thought that the operation of the 75 drill will be readily understood by those skilled in the art. When the drill is rotated, the disks 14 will also be rotated upon their alining bearing pins 11 and will cut into the surface thereunder, thus forming 80 an opening sufficiently large to receive the head 1 and the parts connected thereto. A stream of water is directed into the lining tube 5 from the tubular rod, not shown, so that the dust and small particles produced 85 by the cutting disks will be washed out of the bore. The wear plates 7 can be renewed whenever desired and the disk 14 can be readily detached simply by removing the cotter pin 14' and unscrewing the pin 11. 90 By providing the peculiar connections described between the disks 14 and legs 3, danger of the parts becoming accidentally detached, while in use, is reduced to the minimum. 95

It will be noted that the legs 3 are not twisted, as has heretofore been deemed necessary.

What is claimed is:—

1. A drill including a head having spaced 100 legs, concavo-convex disks mounted for rotation relative to and connected to the legs, each of said disks having stepped annular reinforcing portions upon its convex face.

2. A drill including a head having spaced 105 legs, a bearing pin detachably mounted

within each leg, the two bearing pins alining and extending inwardly from the legs, and a concavo-convex cutting disk mounted for rotation on the inwardly extending portion of each pin, said disks being mounted for rotation in parallel planes and each disk having a stepped convex face.

In testimony that I claim the foregoing as my own, I have hereto affixed my signature in the presence of two witnesses.

THOMAS FRANK LITAKER.
